Patented Aug. 31, 1971

221,618

COMBINED DISPENSING BOTTLE AND CLOSURE THEREFOR

Howard J. Levin, Norristown, and Stephen W. Goodsir,
King of Prussia, Pa., assignors to American Home
Products Corporation, New York, N.Y.

Filed Mar. 4, 1970, Ser. No. 21,730

Term of patent 14 years

Int. Cl. D9—01

U.S. Cl. D9—2

FIG. 3

FIG. 4

FIG. 1

FIG. 2

FIG. 5

FIG. 6

FIG. 1 is an elevational view of a combined dispensing bottle and closure therefor showing our new design;

FIG. 2 is an elevational view looking from the left of FIG. 1;

FIG. 3 is a top plan view;

FIG. 4 is a fragmentary sectional view taken on the line 4—4 of FIG. 3;

FIG. 5 is an exploded elevational view; and

FIG. 6 is a top plan view taken on the line 6—6 of FIG. 5.

We claim:

The ornamental design for a combined dispensing bottle and closure therefor, substantially as shown.
